UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

FILING APPLIANCE.

1,031,021.

Specification of Letters Patent.

Patented July 2, 1912.

Application filed October 18, 1906. Serial No. 339,539.

To all whom it may concern:

Be it known that I, WILLIAM H. MUZZY, a citizen of the United States, residing at Dayton, in the county of Montgomery and 5 State of Ohio, have invented certain new and useful Improvements in Filing Appliances, of which I declare the following to be a full, clear, and exact description.

This invention relates to improvements in 10 filing cases or cabinets and has more particular relation to improvements in cabinets for filing counter sale slips.

The principal object of the invention is to 15 provide an improved cabinet with compartments in which the sale slips may be quickly inserted.

Another object is to provide a cabinet in which the total of a slip may be instantly 20 read without any chance of confusing it with the other slips in adjacent receptacles.

A further object of the invention is to 25 provide means whereby the receptacles are automatically secured in adjusted positions for the taking of the totals and the insertion of new slips.

With these and incidental objects in view, 30 the invention consists in certain novel features of construction and combination of parts, the essential elements of which are set forth in appended claims and a preferred form of embodiment of which is herein-after specifically described with reference to the drawings which accompany and form part of this specification.

35 Of said drawings: Figure 1 represents a perspective view of the cabinet embodying the present invention; one of the compartments being exposed. Fig. 2 represents a central vertical section through the same.

40 Fig. 3 represents a detail perspective view of one of the slip receiving trays or compartments and a portion of the back plate. Fig. 4 represents a vertical transverse section through the tray, on the line 4—4 of

45 Fig. 3, looking in the direction of the arrow, and Fig. 5 represents a detail vertical section through a portion of the auxiliary check file.

50 Described in general terms the present invention may be said to comprise a series of pivoted trays which, when elevated, are secured in this elevated position by automatic bails pivoted to the undersides of the respective trays and arranged to rest upon the 55 trays immediately beneath them. The trays

are also provided with card attaching means for the names of several customers and, also with guarding plates which normally conceal the portions of the slips containing the totals of the several accounts. 60 These guards are so arranged as to fully expose the totals when the receptacles are elevated. In connection with this slip file I provide an auxiliary file arranged to receive the stiff cardboard cash register checks covering petty sales in which the customer did not have time to wait to have the regular slip made out. 65

In connection with this cabinet a triplicate manifolding book is employed. 70

Any well known form of book may be used, as there are many forms now on the market, consisting of a plurality of sets of slips, each set comprising a first, a second and a third slip, and sets being all bound together 75 into book form. One of the three slips of a set from the triplicate book is placed in the cabinet, another in the cash drawer of the cash register and the third given to the customer. By this means the clerk is reminded each time a credit sale is made to register the same on the register, because until this registration has taken place the cash drawer is inaccessible for the reception of the second slip. The slips employed in connection with this cabinet also carry the totals forward at the lower right hand corner of the slip so that the total amount owing by any customer may be instantly ascertained by simply raising the receptacle 80 above that in which the customer's account is located and glancing at the lower right hand corner of the slips. The proprietor in checking over the slips at night is only compelled to check over the slips in the cash 85 drawer, which represent the sales made during that day. These slips in the cash drawer are taken out at night and placed in a suitable card system filing device. The totals which are carried forward are compared by the proprietor with the previous totals and he is at once able to check his clerks who might have omitted to place some certain slip in the cabinet and thus leave an improper total to be copied by the next 90 clerk making a sale to that customer. The third slips may also be placed in a safe or carried home and thus provide protection or checking means if the cabinet is destroyed by fire. 95

The casing of the cabinet comprises sides 2 and 3, top 4, bottom 5 and a back 5^a. A sliding drawer 6 is provided in the base of the cabinet in which may be kept the blank books or, if desired, this drawer may be used to temporarily hold the filing devices for the third slips.

A plurality of trays or receptacles 7 are provided and it will be evident that these 10 may be increased or diminished in number as desired, such change in number being a matter of mere duplication. As shown the cabinet is of a size adapted to contain four rows of receptacles arranged in vertical 15 columns and having metal partitions 8 between the various columns, and a hinged metal plate 7^a over the top tray of each column.

An inclined false back 10 shown in Fig. 20 2 is provided in the cabinet and is adapted to support the rear ends of the receptacles. Mounted on this back are a series of strips of metal, 11, shown best in Fig. 3. The middle part of each of these strips extending 25 its full length, is raised above the two outer portions. This middle part is thus raised to allow the hinge tongues of the receptacle bases to be inserted through slots therein. The receptacles are made 30 preferably from sheet metal and include a bottom 13 from which sides 14 are bent upward and then inward, as indicated at 15. The rear ends of the receptacles are provided with tongues 16 adapted to pass 35 through slots 16^a in plates 11. At the forward right hand end of the receptacle the metal is bent forward and downward forming a guard 18 and to the left of this guard is bent upward at 19 to form a name plate 40 and downward at 20 to provide a front for the receptacle and a support for the receptacle above. A tongue 21 is cut from the upwardly bent portion 19 and projects forward from the bottom to provide a finger 45 piece by means of which the receptacle may be raised. Depending lugs 22, one at each side, are stamped from the material of the tray and are apertured to receive a supporting bail 23. The name plate 19 is 50 formed with projections 25 which are bent to form flanges for supporting a card bearing the name of the customer and which is slipped in from the top. A wire 31 extends over the forward end of each receptacle 55 from side to side forming a retaining device for the slips. The guards or plates 7^a are similar to the trays except that the front name plate and supporting flange are omitted.

60 At the right of Fig. 1 is a filing device 32 divided into compartments which are marked with the letters of the alphabet and provided with retaining springs 33 arranged to hold the cash register checks in 65 position when placed therein.

The operation of the system is as follows: When a credit sale is made the clerk enters the various items on his manifold account book then goes to the filing cabinet and places his finger under the projecting portion 21 of the receptacle above the one bearing the name of the customer. When the receptacle is elevated above the one to which access is desired all the receptacles over the same are also raised. As the receptacle is raised the bail 23 drops automatically, as indicated in Fig. 3 and also shown in Fig. 1, to a position in which it will support the raised receptacles. The clerk can now see the total amount of the customer's bill 70 through the space uncovered by the guard 18 and insert the same at the top of the slip which he has previously filled out, see Fig. 75 3. It will be noted that this guard 18 of each receptacle normally conceals the 80 amount indicated on the uppermost slip in the receptacle underneath it. When the total has been entered on the slip the entire amount is then footed and the slips torn out of the book. The third copy as stated 85 is given to the customer serving to show the exact state of his account, the original is placed in the open receptacle and the duplicate is placed in the drawer of a cash register or some auxiliary file which itself may 90 be in the drawer 6 in the base of the device. Each night or whenever desired the proprietor may take the duplicate slips from the auxiliary file and audit the same and 95 compare with previous totals. 100

In a great many instances in actual practice it is found that children and servants and, sometimes, others will hurriedly enter a store to get some small article like a cake of soap, a box of matches, a yeast cake or something of the kind and will not want to wait to have a charge slip made out. In such cases the clerk instead of making out a charge slip at once may register the amount on the cash register and then place 110 the check, which the register delivers, in the proper receptacle 32. Before closing time in the evening, regular sales slips are made out for the checks which are placed in these different receptacles and the checks then destroyed. The clerk before placing the check in the receptacle, of course, writes the name of the purchaser on the back of the check and, also the article whether soap, matches, or whatnot, there never being more than 115 one article. 120

It will be seen that the system used with this filing cabinet is very simple and yet that there is small liability of mistakes. The account of each customer is kept entirely separate and takes only a small amount of room. Moreover the exact state of the account is to be had by a mere glance at the topmost slip. There is little chance for customers to complain that their slip 125 130

does not agree with the amount charged as they have at every sale kept a slip including the footings of the accounts.

It will be noted that the system may be used in connection with a duplicate manifold book also, but in this case the auxiliary filing device would be dispensed with and it will be necessary for the proprietor to look into everyone of the receptacles 10 daily in order to check the extensions and audit the slips. With the triplicate system, however, it is necessary only to examine the slips for which sales have been made on that day and which are kept separate 15 in the cash register drawer or in an auxiliary file.

What is claimed is:

1. In a device of the class described, the combination with a containing casing, of 20 a plurality of movable trays therein having slip retaining portions extending only partly across their outer ends and guard portions extending so as to project over the open front portions of adjacent trays to 25 conceal the slips.

2. In a device of the class described, the combination with a containing casing, of a series of trays pivotally mounted therein and each comprising a base, a slip retaining portion along part only of the outer end of 30 the base, and a concealing flange along the remaining part of the outer end of the base and positioned to extend over the corresponding portion of the adjacent receptacle.

3. A filing device comprising a casing and 35 a plurality of receptacles carried thereby in vertical columns, each receptacle having an integral part for hinging the receptacles in the casing, an integral part bent upward to provide a name plate, and a further part 40 bent downward to provide a guard means overlying the front open portion of the subjacent receptacle.

In testimony whereof I affix my signature in the presence of two witnesses.

WILLIAM H. MUZZY.
